40 Inventor,
R. M. Overton, by
G. Kennedy,
Attorney.

UNITED STATES PATENT OFFICE.

ROBERT M. OVERTON, OF WATERLOO, IOWA.

CLOTHES-DRYING DEVICE.

Application filed February 24, 1921. Serial No. 447,562.

To all whom it may concern:

Be it known that I, ROBERT M. OVERTON, a subject of the King of Great Britain, and a resident of Waterloo, Black Hawk County, 5 Iowa, have invented certain new and useful Improvements in Clothes-Drying Devices, of which the following is a specification.

My invention relates to improvements in clothes drying devices. One object of my 10 improvements is to furnish a hollow, closed, foldable sectional casing or drying container for damp clothes, adapted to be connected removably to or placed in juxtaposition to a washing machine, and having therein or 15 positioned to propel an air-current through it, a rotatable fan-wheel adapted to be actuated by a motor as that of the washing machine, the casing folding into small compass for storage or transportation when not in 20 use.

Another object of my improvements is to associate with said casing a plurality of clothes holders, arranged therein in spaced 25 arrangement, permeable to an air-current driven therethrough by said fan-wheel, and having spacing members which also serve to 30 releasably clamp articles of clothing or any textiles upon the holders in a spread out and loose condition favorable to quick drying under the action of the air-current.

These objects have been accomplished by the means which are hereinafter described and claimed, and which are illustrated in the accompanying drawings, in which Fig. 1 is a perspective view of my improved clothes 35 drying device as mounted upon a washing machine; Fig. 2 is a plan of the casing with the cover removed, showing the clothes holding means therein; Fig. 3 is a detail side elevation of two of the superposed clothes 40 holders, and Fig. 4 is an end elevation of the same.

Similar numerals of reference denote corresponding parts throughout the several 45 views.

My improved clothes drying device has a foldable casing or container made of hinged- 50 ly connected sections. To a horizontal rectangular bottom plate 1, like side plates 3 and 4 are connected by means of hinges 2. One end of the casing may be left open as shown, and there is an end closure 9 at the opposite end, the latter connected to the bottom plate by hinges 10. A flanged top cover 55 6 is hinged to the side plate 4 by hinges 5, and has a slotted hasp 7 for engagement with

a staple 8 on the outside of the side plate 3. The side and end plates may be releasably secured together by any fastening means, such as overlapped orificed lugs 35 connect- 60 ed by split-pins. On the outside of the side plates at their lower corners, may be fixed sockets 36 in which legs 37 may be removably mounted, and fastened in any desired way. A hooked rod 13 may be pivoted to 65 the top of the end plate 9 to releasably engage a stud 14 on an end flange of the cover plate 6 to prop the latter in an open position. When one end of the casing is left open as shown, the upper corners of the side 70 plates at that end may be detachably connected to a curved cross-bar 15, which permits the end of the casing to be brought into close juxtaposition with a cylindrical wash- 75 ing machine 18 to which it may be releasably fastened by hook and staple connections 16 and 17.

The motor, not shown, of the washing machine 18, may have a projecting power-shaft 19 provided with a terminal belt-pulley 20 carrying the lower end of a driving belt 21. An orificed bearing-body 28 is fixed on the middle of the curved cross-bar 15 and in it is rotatably mounted a short shaft on which the fan wheel 22 is loosely and removably mounted together with a belt pulley rigidly connected thereto having a clutch member. Said belt 21 passes about the pulley 24, and a clutch sleeve 25 is slidably, non-rotatably mounted on said shaft for occasional engagement with the clutch face on 85 said pulley. The clutch-sleeve is annularly grooved to receive a terminal fork 26 on a reversely bent arm 27 which latter may be used to shift the clutch sleeve into or out 90 of engagement with said pulley's clutch face.

When the clutch-sleeve 25 is engaged with said pulley clutch-face the pulley 24 is locked against rotation, the driving-belt 21 sliding around the pulley, being somewhat loose, as the fan requires but little tractive power while in operation.

Openings 11 may be provided in the ends of the side plates 3 and 4 adjacent said washing machine, and the end plate 9 may have a 105 number of louvered openings 12.

The device so far described, may be successfully employed in the drying of clothes when the damp clothes are disposed within said casing upon any kind of supporting means which will permit them to be in a loose or spread out condition to permit air 110

currents, propelled by said fan wheel, to forcibly permeate them.

I have shown, however, certain means for performing this function which are thought to be of superior convenience and utility. An orificed partition may be removably mounted across the interior of the casing immediately to the rear of said fan wheel 22 as a safeguard for the operator, and may be 10 constructed of a rectangular open frame 30 carrying a large meshed netting, the uprights of said frame being slidably seated between lugs on bodies 29 bracketed on the inner walls of the side-plates 4 near their 15 tops. This partition divides the interior of the casing in two compartments of which the larger one is used as the clothes drying chamber. On the inner walls of said side plates, near the lower edges and near the 20 said partition, are fixed bracketed bodies 31 having vertically orificed horizontal parts in which are stepped the lower ends of vertical rods 32.

Referring to Figs. 2 to 4, inclusive, the 25 numeral 34 denotes one of a plurality of like tabular clothes holders, preferably having open frames covered with large mesh netting 38. These holders are placed in said clothes drying chamber in spaced superposition 30 successively, to a desired number, but it is good practice to have the heights of spacing between the holders of the same heights of the louver openings 12 positioned at the same level for freer transmission of air currents therethrough. The ends of the holders 34 adjacent said end plate 9 may have short legs 39 fixed thereon to support the 35 superposed holders in spaced relation.

The opposite end of each holder 34 has a 40 spaced pair of like downwardly bifurcated legs 40 fixedly mounted on the cross bar 12, whose forks are placed astride of the like cross bar of the holder below to serve as spacing legs. Referring to Fig. 2, it will be 45 seen that said bifurcated legs 40 have the further function of serving as securing means by which to hold or releasably fasten a spread out piece of cloth or garment 41 upon the netting of a holder, the weight of 50 the holder above thus serving to secure the cloth at its end nearest the fan wheel 22, the other end of the cloth being left free to flap in the strong air current propelled by the fan wheel. Preferably, but a single layer of 55 the textile should be placed upon a holder so that evaporation may more rapidly occur to effect quick drying. In this way, when all the holders are used a full charge can be received thereon after washing in the machine 18, the operation of the fan wheel sufficing to thoroughly dry the clothes during 60 the time that another charge is being washed in said machine.

It is to be understood that the fan wheel or other air propelling means may be actuated

by any other motor connection which may be suitable and available, as the device is not necessarily restricted to be an attachment to a washing machine.

The numeral 31 denotes orificed lugs fixed 70 on the lower inner faces of the side plates 3 and 4 to receive standard rods 32. Orificed lugs 33 are fixed on both sides of the holders 34 to have their orifices in vertical alignment with the orifices in said lugs 31, the rods passing therethrough to position and detachably secure the holders 34 in superposition.

Having described my invention, what I 80 claim as new and desire to secure by Letters Patent, is:

1. A device of the character described, comprising a hollow collapsible casing having inlet and outlet ports and a removable orificed partition therein, and means within 85 and for creating an air-current through said casing partition.

2. A device of the character described, comprising a hollow casing composed of 90 foldably-connected sections provided with openings, a rotatable fan-wheel positioned in said casing, and an orificed partition dividing the interior into a fan-wheel chamber and a clothes-receiving chamber.

3. A device of the character described, 95 comprising a hollow casing having air-ports at its opposite ends, a fan-wheel rotatably mounted in one end of said casing, a plurality of orificed tabular clothes-holding bodies 100 removably and separably mounted in juxtaposition in said casing and positioned lengthwise therein relative to said fan-wheel between said end air-ports.

4. A device of the character described, 105 comprising a hollow casing having air-ports in its opposite ends, a fan-wheel rotatably mounted in one end of said casing, a plurality of horizontally disposed spaced tabular clothes-holding bodies removably and separably positioned in superposition in said casing, and means for spacing said bodies apart.

5. A device of the character described, 115 comprising a hollow casing having air-ports in its opposite ends, a fan-wheel rotatably mounted in one end of said casing, an orificed partition dividing the interior into a fan-wheel compartment and a clothes-receiving compartment, a plurality of flat orificed 120 superposed spaced horizontal trays positioned in the clothes-receiving compartment, and spacing-supports depending from each tray shaped to fit upon portions of the tray thereunder and to clamp between it and the tray thereunder articles spread flatly upon the latter tray lengthwise in the casing with relation to both said fan-wheel and to said air-ports.

6. A device of the character described, 130 comprising a hollow casing formed of foldably connected sections and having air-ports

at its opposite ends, a fan-wheel rotatably mounted in said casing, standards removably mounted in said casing on opposite sides thereof, a plurality of clothes-holding trays 5 positioned in spaced superposed horizontal relation in said casing between said air-ports and lengthwise with relation to said fan-wheel, said trays having means for clamping flatly thereon articles to be dried, and having other means for releasably securing them 10 to said standards.

Signed at Waterloo, Iowa, this 16th day of Feb., 1921.

ROBERT M. OVERTON.
